US0D1096322S

(12) **United States Design Patent** (10) Patent No.: **US D1,096,322 S**
(45) Date of Patent: ** Oct. 7, 2025

(54) **BOWL**

(71) Applicant: **FUJIAN SHAOWU FULIN
COMMODITY MANUFACTURING
CO., LTD.**, Nanping (CN)

(72) Inventors: **Zhongming Qiu**, Nanping (CN);
Yiping Huang, Nanping (CN); **Zhi
Zou**, Nanping (CN)

(73) Assignee: **FUJIAN SHAOWU FULIN
COMMODITY MANUFACTURING
CO., LTD.**, Nanping (CN)

(**) Term: **15 Years**

(21) Appl. No.: **29/938,212**

(22) Filed: **Apr. 19, 2024**

(30) **Foreign Application Priority Data**
